UNITED STATES PATENT OFFICE.

HEBROW B. LAYMAN, OF NEW YORK, N. Y.

INTERNAL-COMBUSTION ENGINE.

1,244,869.

specification of Letters Patent. Patented Oct. 30, 1917.

Application filed July 13, 1914. Serial No. 850,555.

To all whom it may concern:

Be it known that I, HEBRON B. LAYMAN, a citizen of the United States, and residing at New York, in the county of New York and State of New York, have invented certain new and useful Improvements in Internal-Combustion Engines, of which the following is a specification, such as will enable those skilled in the art to which it apper-

tains to make and use the same.

This invention relates to explosion or internal combustion engines, and particularly to engines of this class of the sleeve valve type, and the object thereof is to improve the construction of, and the method of assembling the parts of, engines of this class, so as to facilitate the finishing and assembling of said parts and render the same more practical and economical and at the same time increase the efficiency of such engines; and with this and other objects in view the invention consists in the construction, combination and arrangement of parts herein-after described and claimed.

This invention is applicable to engines of the class specified, comprising any desired number of units or cylinders, and said invention is fully disclosed in the following specification, of which the accompanying drawing forms a part, in which the separate parts of my improvement are designated by suitable reference characters in each of the views, said drawing being a central vertical transverse section through one cylinder of an engine involving my invention.

In carrying my invention into effect, I provide a cylinder a , the top portion of which is inclosed by a casing b into which the cylinder is inserted from the bottom thereof, and said casing b is inclosed by a supplemental casing or jacket b^2 which is formed integrally therewith and which also incloses the inlet and exhaust manifolds c and d , and the bottom of the casing b is provided with an outwardly directed flange or rim b^3 .

The top of the cylinder a is contracted to form an inwardly directed annular and upwardly inclined wall or shoulder a^8 having a neck portion a^4 which forms the bottom part of the explosion chamber, as herein-after described, and said part a^4 is provided at the top thereof with an outwardly directed, horizontal rim portion a^5 having a

downwardly directed skirt portion a^6 provided at the bottom with an outwardly directed flange a^7 which is above the top of the working portion of the cylinder and on which the bottom flange or rim b^3 of the casing b rests, and between said flange b^3 of the casing b and the flange a^7 at the bottom of the skirt a^6 is placed a packing ring b^4 .

I also provide an explosion head e which involves a main outer cylindrical casing e^2 and which is inserted into the casing b from the top thereof, and between which and said casing b is a sleeve valve chamber f in which is placed a sleeve valve f^2 , and the sleeve valve chamber extends from the top of the parts b and e^2 to the bottom of the part b , and the outer wall of the sleeve valve chamber is formed by the part b , while the inner wall thereof is formed by the part e^2 , and the skirt a^6 at the top of the cylinder.

The explosion head e is provided at the top thereof with an overlapping or cap portion e^3 forming a water chamber h in the top portion of said explosion head, and within said explosion head is another water chamber h^2 , and between the outer casing members b and b^2 is another water chamber h^4 which incloses the inlet and exhaust manifolds c and d and extend downwardly and incloses the top portion of the cylinder in the usual manner, and the water chamber h^4 , the top portion of which incloses the explosion head e , is placed in communication with the water chamber h in the top of said explosion head by ports or passages e^4 .

Within the central top portion of the explosion head e is a cup-shaped chamber e^5 which opens upwardly and in the central bottom portion thereof is another chamber e^8 which communicates with the neck portion a^4 of the cylinder a , and which forms in connection with said neck portion of the cylinder the explosion chamber with which the inlet and exhaust manifolds c and d are placed in communication by ports or passages c^2 and d^2 in the casing member b , and corresponding radial ports or passages i formed in and between the bottom of the explosion head e and the top portion a^5 of the neck a^4 of the cylinder, and which extend through the casing member e^2 of the explosion head.

The chamber e^5 in the top portion of the

explosion head, and the chamber e^8 in the bottom portion thereof and which forms a part of the explosion chamber are separated by a central neck portion or partition e^9 having a threaded aperture e^7 into which, in practice, the sparking plug is screwed in the usual manner, and around the neck portion a^4 of the cylinder, or between said neck portion and the skirt member a^6 is an annular water space or chamber h^6 which communicates with the water chamber h^4 around the cylinder, and which also communicates with the water chamber h^2 in the explosion head, the water being free to pass upwardly between the radial ports or passages i , and with this construction there is a continuous flow of water from the radiator upwardly around the cylinder through the explosion head and on the inner side of the valve chamber, or the inner wall thereof, and around the inlet and exhaust manifolds c and d , and around the outer wall of the valve chamber up into the cap portion or part e^8 of the explosion head from which the water passes back to the radiator in the usual manner.

In the accompanying drawing, I have shown no means for operating the valve, but it will be understood that said valve may be operated in the usual manner, or by any preferred means, such, for instance, as that shown and described in U. S. Letters Patent No. 1,063,082, of May 27, 1913, or No. 1,017,073 of February 13, 1912.

It must also be understood that the explosion head e , or the bottom thereof, abuts on or against the top of the neck a^4 of the cylinder, as shown at g , and this connection between said parts may be packed in any desired manner.

The main feature of my improvement is found in the fact that the cylinder is open at the top and is adapted to be passed upwardly into the casing member b , while the explosion head e is passed downwardly into the casing member b and the valve chamber, or the walls thereof, are formed by the explosion head, or the casing member e^2 thereof, and the skirt member a^6 at the top of the cylinder and the main outer casing member b and, as will be understood, this construction facilitates the formation of all of the said parts, and the machining and finishing of the valve chamber and the connection of the various parts, and renders the said operation or operations more simple and effective and at the same time more economical than is usual in this class of devices.

Having fully described my invention, what I claim as new and desire to secure by Letters Patent, is:—

1. In an explosion engine, a main cylindrical casing, a cylinder the top portion of which is insertible into the bottom of said

casing, and an explosion head member insertible into the top portion of said casing, a sleeve valve chamber between said casing and said explosion head and the top part of the cylinder, said top portion of the cylinder and the bottom of the explosion head abutting, and being provided with radial inlet and exhaust ports which communicate with inlet and exhaust manifolds and with an explosion chamber formed partly in the top part of the cylinder and partly in the bottom part of the explosion head.

2. In an explosion engine, a main cylindrical casing, a cylinder the top of which is inserted into the bottom of said casing, an explosion head which is inserted into the top portion of said casing, a sleeve valve chamber formed between said casing and the explosion head and the top part of the cylinder, and an explosion chamber formed partly in the top of the cylinder and partly in the explosion head and provided with radial ports or passages which communicate with inlet and exhaust manifolds, and means whereby water may be circulated upwardly around the cylinder and on both the inner and outer sides of the sleeve valve chamber.

3. In an explosion engine, a main cylindrical casing, a cylinder provided with a top portion which is inserted into the bottom of said casing, an explosion head inserted into the top portion of said casing and provided with a cap, a sleeve valve chamber formed between said casing and the explosion head and the top portion of the cylinder, an explosion chamber formed partly in the explosion head and provided with radial ports or passages which communicate with inlet and exhaust manifolds, and means whereby the water may be circulated upwardly around the cylinder and on the outer side of said casing and between the explosion chamber and the sleeve valve chamber and into the cap of the explosion head.

4. In an explosion engine, a main cylindrical casing having inlet and exhaust manifolds, a cylinder the top of which is inserted into the bottom portion of said casing, and an explosion head inserted into the top portion of said casing, the explosion chamber being formed partly in the top portion of the cylinder and partly in the explosion head, and means whereby water may be circulated upwardly and continuously through the explosion head and between the explosion chamber and valve chamber.

5. In an explosion engine, a main cylindrical casing having inlet and exhaust manifolds, a cylinder the top of which is inserted into the bottom portion of said casing, and an explosion head inserted into the top portion of said casing, the explosion chamber being formed partly in the top portion of the cylinder and partly in the explosion

head, and means whereby water may be circulated upwardly and continuously through the explosion head and between the explosion chamber and valve chamber and on the outer side of said valve chamber.

In testimony that I claim the foregoing as my invention I have signed my name in

presence of the subscribing witnesses this 11th day of July, 1914.

HEBRON B. LAYMAN.
